LIQUID-DISPENSING DEVICE.

1,075,898.

Specification of Letters Patent. Patented Oct. 14, 1913.

Application filed May 3, 1912. Serial No. 694,923.

To all whom it may concern:

Be it known that we, JOSEPH H. CHAMP and THEODORE H. SCHUTT, citizens of the United States, and residents of Cleveland, county of Cuyahoga, and State of Ohio, have jointly invented a new and useful Improvement in Liquid-Dispensing Devices, of which the following is a specification, the principle of the invention being herein explained and the best mode in which we have contemplated applying that principle, so as to distinguish it from other inventions.

The present improved apparatus, while generally adaptable to the dispensing of liquids, is more especially designed with regard to the dispensing of syrups and the like, as at soda fountains.

The object of the invention is to provide a simple and automatically operable device that when the faucet handle is turned will discharge a predetermined, or measured, quantity of the syrup or other liquid.

A further object is to provide means for eliminating the dripping, which is an annoying incident to the operation of such faucets as at present constructed.

To the accomplishment of the foregoing and related ends, the invention, then, consists of the means hereinafter fully described and particularly pointed out in the claims.

The annexed drawings and the following description set forth in detail certain mechanisms embodying the invention, such disclosed means constituting, however, but several of the various mechanical forms in which the principle of the invention may be used.

In said annexed drawings:—Figure 1 is a central vertical section of a device or apparatus embodying our present improvement; Figs. 2, 3 and 4 are transverse sectional views of such device taken on planes indicated by the correspondingly numbered lines on Fig. 1; Fig. 5 is a view corresponding to Fig. 1, but showing a modification in the construction of the device; Figs. 6 and 7 are transverse sectional views of such de-

vice taken on planes indicated by the correspondingly numbered lines on Fig. 5; Fig. 50 8 is a view similar to Fig. 1, but illustrating yet another modification in the construction of the device; and Figs. 9, 10 and 11 are transverse sectional views of such device taken on planes indicated by the correspondingly numbered lines on Fig. 8.

The syrup is designed to be supplied to the dispensing device, which forms an object of present interest, under suitable pressure, and it is immaterial whether this pressure is secured by gravity, that is, by having the supply tank at a relatively higher elevation than the dispensing apparatus, or whether it be secured by placing such tank under air or other gaseous pressure. The device 65 itself, having reference to the constructional form illustrated in Figs. 1 to 4, inclusive, comprises primarily a cylindrical chamber 1 having an inlet connection 2 for the supply thereto of syrup from a source such as 70 just described. Chamber 1 is preferably vertically disposed and within it is reciprocably held a piston 3 of such weight as to normally sink to the bottom of the chamber, or rather into contact with an adjustable 75 stop 4 mounted in such bottom, whereby the downward movement of the piston may be regulated. Provision is made, however, that under no circumstances shall the piston entirely close connection across the bottom of 80 the chamber between the inlet opening 2 previously referred to, and a second opening 5 that is connected with a by-pass 6 leading to a valve casing 7 at a point conveniently located above the piston chamber. 85 Such valve casing is adapted to receive a valve plug 8 of familiar tapered form, operable by a handle 9, and constitutes the dispensing faucet. Valve plug 8 is provided with a central passage 10 having apertures 90 or ports 11 and 12, adapted in one position (that shown in Fig. 1) to afford free communication between the upper portion of the piston chamber 1 and the by-pass 6, thus 95 equalizing the pressure on both sides of the piston so that the latter will drop to the

bottom of the chamber by reason of its weight. The portion of the chamber above such piston is thereupon, of course, filled with syrup which is admitted thereto through the by-pass. Other ports 13 and 14 in the valve plug serve, in a position of the latter angularly related to the position just described, to connect the upper portion of the piston chamber 1 with the discharge 5 opening or mouth 15 of the faucet, the connection with the by-pass 6 being simultaneously closed. In this last-described position of the valve plug, the pressure on the upper side of the piston is, of course, relieved so that the force of the syrup on the under side thereof raises said piston and causes the syrup in the upper portion of said chamber to flow from the valve and be discharged from the latter's mouth. The 10 casing 7 is formed with an opening 24, and in the closed position of the valve plug communication is established between this opening and the discharge mouth 15 by a groove 23 formed in the valve plug. When the 15 valve is in closed position therefore, the discharge mouth is open to atmospheric pressure both from above and below, and consequently any syrup remaining in the discharge mouth will tend to run out instead 20 of gradually dripping from the mouth. The piston carries a stopper valve 16 on its upper face that is adapted to tightly close the opening 17 in the upper end of such chamber when the piston is raised, thus 25 making it unnecessary that the piston be tightly fitted in said chamber. Upon restoring the handle 9 of the valve to its normal position, the pressure on the top and bottom of the piston is again equalized and 30 the upper portion of the piston chamber filled with syrup, the quantity being determined by the location of the stop which limits, as before stated, the downward movement of the piston.

35 In the modification of the construction illustrated in Fig. 5, substantially the same arrangement of piston and by-pass obtains as in the case of the first described form of the invention, and these parts are correspondingly designated. A more extended 40 discharge tube or mouth-piece 18, however, is provided in connection with the valve that controls the operation of the device, and in addition to the passage in the valve plug 45 and ports for variously connecting such passage, attention is directed to the lateral extension of the port 11 controlling the upper by-pass connection. This lateral extension 50 serves, as the valve plug is being restored 55 to its normal position, to admit a small quantity of syrup under pressure into the passage 10 in the plug, while the port 14 in the latter is still connected with the discharge 60 15. This syrup under pressure causes the

body of syrup already in the discharge tube 65 18 to be forced out with a final squirt that more or less completely empties the discharge tube and tends to prevent any dripping such as would otherwise occur, if any considerable quantity of syrup were left in 70 the tube. Instead of utilizing an additional small quantity of syrup under pressure to effect this final discharge of syrup from the mouth-piece, we may employ a pressure fluid, such as air or carbonic acid gas, both 75 of which are usually available about soda water fountains. An adaptation of the construction for this purpose is illustrated in Figs. 8 to 11 inclusive, where again the general arrangement and operation of the parts 80 is the same as in the first described construction, with the addition of a special discharge tube or mouth piece 18. The valve casing 7, however, is provided with an additional connection 20 whereby air may be 85 brought thereto, and in proper position of the plug 8 be admitted into the discharge opening 15 through grooves 21 and 22 forming passages in the bearing surface of the plug, as shown in Figs. 8 and 9. The disposition of these latter passages is such that the air is admitted in small quantity incidentally to the restoring of the valve to its 90 normal position, the effect being to force out the residual syrup collecting in the discharge 95 tube of the device so that dripping is prevented. It is, of course also undesirable that this syrup should be allowed to collect in said tube, as it will dry and tend to clog up the same.

100 Other modes of applying the principle of our invention may be employed instead of the one explained, change being made as regards the mechanism herein disclosed, provided the means stated by any of the following claims or the equivalent of such stated means be employed.

105 We therefore particularly point out and distinctly claim as our invention:—

1. In apparatus of the class described, the 110 combination of a measuring chamber having an inlet and an outlet at opposite ends; a member reciprocable in said chamber and normally positioned at the inlet end thereof; connections normally open for supplying 115 under pressure the liquid to be measured to both ends of said chamber; and valve means adapted to close said connections to the outlet end of said chamber and open the latter to discharge.

120 2. In apparatus of the class described, the combination of a measuring chamber having an inlet and an outlet at opposite ends; a piston reciprocable in said chamber and normally positioned at the inlet end thereof; adjustable means for limiting such normal position of said piston; connections normally open for supplying under pressure to both

- ends of said chamber the liquid to be measured; and valve means adapted to close said connections to the upper end of said chamber and open the outlet of the latter to discharge.
3. In apparatus of the class described, the combination of a substantially vertically disposed measuring chamber having an inlet at its lower end and an outlet at its upper end; a piston reciprocable in said chamber and normally held by gravity at the lower end thereof; connections normally open for supplying under pressure to both ends of said chamber the liquid to be measured; and valve means adapted to close said connections to the upper end of said chamber and open the outlet of the latter to discharge.
4. In apparatus of the class described, the combination of a substantially vertically disposed measuring chamber having an inlet at its lower end and an outlet at its upper end; a piston reciprocable in said chamber and normally held by gravity at the lower end thereof; an adjustable stop in the bottom of said chamber adapted to limit such normal position of said piston; connections normally open for supplying under pressure to both ends of said chamber the liquid to be measured; and valve means adapted to close said connections to the upper end of said chamber and open the outlet of the latter to discharge.
5. In apparatus of the class described, the combination of a substantially vertically disposed measuring chamber having an inlet at its lower end and an outlet at its upper end; a piston reciprocable in said chamber and normally held by gravity at the lower end thereof; a valve carried by said piston and adapted to close the outlet of said chamber; connections normally open for supplying under pressure to both ends of said chamber the liquid to be measured; and valve means adapted to close said connections to the upper end of said chamber and open the outlet of the latter to discharge.
6. In apparatus of the class described, the combination of a measuring chamber having an inlet and an outlet at opposite ends; a piston reciprocable in said chamber and normally positioned at the inlet end thereof; a by-pass connecting the ends of said chamber; and valve means adapted simultaneously to break such by-pass connection and to open the outlet of said chamber to discharge.
7. In apparatus of the class described, the combination of a measuring chamber having an inlet and an outlet at opposite ends; a member movable in said chamber and tending to remain at the inlet end thereof under equal conditions of pressure at both ends of said chamber; and means adapted to relieve the pressure at the outlet end of said chamber.
8. In apparatus of the class described, the combination of a substantially vertically disposed measuring chamber having an inlet at its lower end and an outlet at its upper end; a by-pass connected to the ends of said chamber; a piston reciprocable in said chamber and normally held by gravity at the lower end thereof; and valve means adapted simultaneously to break such by-pass connection and to open the outlet of said chamber to discharge.
9. In apparatus of the class described, the combination of a substantially vertically disposed measuring chamber having an inlet at its lower end and an outlet at its upper end; a by-pass connected to the ends of said chamber; a piston reciprocable in said chamber and normally held by gravity at the lower end thereof; an adjustable stop in the bottom of said chamber adapted to limit such normal position of said piston; and valve means adapted simultaneously to break such by-pass connection and to open the outlet of said chamber to discharge.
10. In apparatus of the class described, the combination of a substantially vertically disposed measuring chamber having an inlet at its lower end and an outlet at its upper end; a by-pass connected to the ends of said chamber; a piston reciprocable in said chamber and normally held by gravity at the lower end thereof; a valve carried by said piston and adapted to close the outlet of said chamber; and valve means adapted simultaneously to break such by-pass connection and to open the outlet of said chamber to discharge.
11. In apparatus of the class described, the combination of a substantially vertically disposed measuring chamber having an inlet at its lower end and an outlet at its upper end; a piston reciprocable in said chamber and normally held by gravity at the lower end thereof; connections normally open for supplying under pressure to both ends of said chamber the liquid to be measured; a discharge tube for dispensing such liquid; valve means adapted to close said connections to the outlet end of said chamber and connect the same with said discharge tube; and connections, likewise controlled by said valve means, adapted to admit fluid under pressure to said discharge tube to force out substantially all liquid remaining therein, substantially as described.
12. In apparatus of the class described, the combination of a substantially vertically disposed measuring chamber having an inlet at its lower end and an outlet at its upper end; a piston reciprocable in said chamber and normally held by gravity at the lower end thereof; connections normally open for supplying under pressure to both ends of said chamber the liquid to be measured; a

discharge tube for dispensing such liquid; valve means adapted to close said connections to the outlet end of said chamber and connect the same with said discharge tube; and 5 ports in said valve means adapted to temporarily connect said discharge tube directly with said supply connections, whereby liquid under pressure is admitted to said

tube and substantially all liquid is removed therefrom, substantially as described.
